TOILET KIT

Application filed May 10, 1930. Serial No. 451,466.

This invention relates to toilet kits and particularly to a kit or pack embodying a whisk brush and a shoe polishing pad. Preferably the kit is made in such size as may be placed conveniently in a lady's hand bag, and the object of the invention is a construction of the kit with a pocket for the brush, a pocket for the fingers by means of which the kit is held while using the polishing pad, and a cover or casing so made and disposed as to prevent the face of the shoe polishing pad ever having to come into contact with the inside of the hand bag, or the brush, or the fingers when in the finger pocket.

Other objects of the invention will appear as the following description of a preferred embodiment thereof proceeds.

In the drawings in which the same characters of reference are used throughout the several figures to denote identical parts;

Figure 1 is a perspective view of the toilet kit embodying the principles of the present invention;

Figure 2 is a longitudinal section taken along the line 2—2 of Figure 1;

Figure 3 is a cross-section taken along the line 3—3 of Figure 2;

Figure 4 is a cross-section showing the cover flap reversed to form the finger pocket, the section being taken along the line 4—4 of Figure 5;

Figure 5 is a vertical cross-section through the kit when in the position shown in Figure 4, the brush being removed; and

Figure 6 is a perspective view showing the cover flap extended.

Referring now in detail to the several figures, the toilet kit comprises a casing or cover designated in general by the reference character 1, comprising front and back flaps 2 and 3, said flaps being integral or joined at one side as indicated at 4 in Figure 3. The back flap has a tab portion 5 extending over the front flap and fastening means such as the glove fastener 6 is employed for snapping the flaps together.

It will be noted from Figure 3 that a partition 7 extends from one side of the kit to the other within the flaps when the latter are in closed position, said partition being sewn

or otherwise secured to the sides of the front flap and being constituted preferably by a piece of skin-on which the fleece 8 is left, said fleece facing outwardly toward the outer flap. It is apparent that when the glove fastener is separated and the back flap is folded into a reversed position as indicated in Figure 4, the fleece is exposed and is in position to be used as a polishing medium.

When the back flap 3 is reversed as shown in Figure 4, the glove fastener may be again snapped, the back flap then forming a pocket for the fingers. By slipping the fingers into this pocket the kit may be operated to move the fleece back and forth upon the shoes or any other surface to be polished without the fingers coming into contact either with the shoes or the fleece.

The space formed between the partition 7 and the front flap constitutes a housing or sheath for the brush 9 and it is to be observed that when the brush is in place within said sheath, it is on the side of the partition 7 opposite to the fleece, and therefore, it is impossible for the brush to come into contact with the fleece. Even when the back flap is reversed to form the finger pocket, the relation of the brush to the partition 7 remains unchanged.

As noted in Figure 4, it is entirely practicable to polish the shoes while leaving the brush in its sheath without the brush coming into contact with the fleece or shoes.

When the kit is in the closed position, as illustrated in Figures 1 and 3, in which it is ready to be placed in the lady's hand bag, it will be noted that the back flap 3 covers the fleece and prevents the latter coming into contact with the lining or contents of the hand bag.

While I have above described what I believe to be a preferred and practical embodiment of my invention, it is to be understood that the changes in the arrangement or disposition of parts can be contemplated providing that the essential principle of the invention as claimed be retained.

What I claim is:

1. A toilet kit comprising a casing includ-

- ing front and back sides permanently secured together along lateral edges forming a brush holding sheath having a polishing fleece on the outside of one side, a flap hingedly supported by said sheath at one side thereof and foldable in either direction, means for fastening said flap on either side of said sheath, said flap forming alternatively, a cover for said fleece and a finger loop for inserting the fingers when operating said polishing fleece, whereby said sheath with the brush inserted therein forms a pad between the finger loop and the fleece to constitute a yielding backing for said fleece.

2. A toilet kit comprising a casing including front and back sides secured together along lateral edges forming a brush holding sheath having a rubbing surface on the outside of one side, a flap hingedly supported by said sheath at one side thereof and foldable in either direction, means for fastening said flap on either side of said sheath, said flap forming alternatively, a cover for said rubbing surface and a finger loop for inserting the fingers when operating said surface, whereby said sheath with the brush inserted therein forms a pad between the finger loop and the rubbing surface to constitute a yielding backing for said surface.

30 In testimony whereof I affix my signature.

LAWRENCE EBERT GÖELLER.
